W. H. HILL

VAPORIZER

Filed March 22, 1923.

Patented Sept. 7, 1926.

1,599,131

UNITED STATES PATENT OFFICE.

WILLIAM H. HILL, OF CANTON, OHIO.

VAPORIZER.

Application filed March 22, 1923. Serial No. 626,777.

This invention relates to liquid fuel vaporizing devices of the kind disclosed in my prior U. S. Patents Nos. 1,436,099 and 1,436,100, which are particularly intended for completing the volatilization of fuels which have been partly volatilized by the action of a carburetor in which the atomized fuel has been mixed with its proper proportion of air to produce the desired explosive mixture.

The invention aims particularly to improve devices of the type disclosed in my prior patents with respect to the means for directing the unvolatilized portions of the fuel mixture against the heated portions of the surface of the vaporizer by which the vaporization or volatilization of these unvolatilized portions of the fuel is accelerated or effected. The invention aims further so to design the passageways through the vaporizing apparatus as to reduce to a minimum the resistance of the apparatus to the passage of the fuel mixture therethrough, while at the same time insuring the maximum action of the apparatus in completing the vaporization of the fuel.

Other objects and important features of the invention will appear from the following description and claims when considered in connection with the accompanying drawings, in which—

Fig. 1 is a vertical elevation of a vaporizing device involving the present invention;

Fig. 2 is a section on the line 2—2 of Fig. 1;

Fig. 3 is a section on the line 3—3 of Fig. 2;

Fig. 4 is a sectional detail showing the construction of the helical passageway between the inlet and the outlet;

Fig. 5 is a section on the line 5—5 of Fig. 4; and

Fig. 6 is a view illustrating the development of the cross sectional contour of the opening into the outlet 2.

The illustrated vaporizing device, like that shown in my Letters Patent No. 1,436,100 comprises a vertical cylindrical casing or chamber 2 having a reduced lower end 4 connected to the upper cylindrical part by a funnel-like portion 6, the lower end 4 of the casing or chamber being adapted to be located within an exhaust passageway 8 in a casing 10 which may be inserted in the exhaust from the motor or in a by-pass from the exhaust.

It will be noted that the cylindrical casing or chamber 2 is provided with a flange 12 seated in a corresponding recess or seat surrounding the opening in the casing 10 through which the reduced lower part of the casing 2 extends. The reduced part 4 of the casing 2 has a threaded lower end 14 to receive a nut 16 by which the casings 2 and 10 are clamped together.

As in the construction shown in my prior patents, the reduced lower end 4 of the casing 2 is preferably provided with heat-collecting flanges 18 to increase the heating action of the exhaust passing over this part of the casing, the upper cylindrical part 2 of the casing being heated only by conduction up the walls of the casing.

The cylindrical chamber or casing 2 has at its upper end an outwardly extending flange 20, to which is clamped a member 22 serving both as a cover for the chamber or casing 2 and as a support for a depending outlet tube or pipe 24 preferably formed integral with the cover and having its outlet opening into the chamber 2 flared as shown at 26 to reduce the resistance to the passage of the fuel mixture therewith from the chamber 2. The curve of this outwardly flared portion 26 of the outlet 24 may be of any suitable character which will effect a reduction in the resistance of the tube to the entry of the fuel mixture therewith, the illustrated curve, the development of which is shown in Fig. 6, being one ascertained by engineers at the U. S. Naval Academy to be possibly the most efficient for this purpose.

The inlet into the chamber 2 for the fuel mixture coming from the carburetor is shown at 28 and, as shown particularly in Fig. 3 of the drawings, is arranged to direct the incoming fuel mixture tangentially against the inner wall of the casing or chamber 2 so that as the fuel travels around the inner surface of the chamber 2 the centrifugal action of the heavier portions of the fuel, which will naturally be the unvolatilized portions, will cause them to strike against said inner surface and to adhere thereto and run down this surface which, as above pointed out, will be heated by conduction from the lower part of the chamber, whereby the vaporization of these unvolatilized portions will be accelerated both by the heat and by their exposure to the air and fuel mixture passing over them.

To insure the maximum of vaporizing action in a structure of minimum dimensions, with a minimum of resistance to the passage of the fuel mixture therethrough, 5 the fuel mixture is preferably confined to a helical passageway extending from the inlet 28 down the wall of chamber 2, between the wall thereof and the tubular outlet 24. As herein shown, this passageway is formed 10 by providing upon the tubular outlet 24 an integral helical flange 30 which extends between the tube 24 and the inner wall of the chamber 2 when the tube with its attached flange is inserted within the chamber; thus defining with the tube and the inner wall of the chamber a helical passage which the fuel mixture is forced to traverse between the inlet and the outlet. For convenience in manufacture of the device the 15 helical flange 30 will also have cast integral therewith a part 32 to engage the inner wall of the chamber 2 adjacent to the inlet 28 so as to confine the incoming gases to the underside of the flange 30 at this point. 20 25 Although, theoretically, the heavier unvolatilized portions of the fuel mixture should be thrown by centrifugal action against the inner wall of the casing 2, it is sometimes found in practice that some of 30 them will touch and adhere to the outer face of the tube 24 and run down this tube. Inasmuch as the tube 24 is not arranged to be heated to the extent that the wall of the casing 2 is intended to be heated, provision 35 is preferably made for collecting these unvolatilized portions which move down the outer face of the tube 24 and direct them again to the inner surface of the casing 2 to insure their contact with the heated part 40 of the apparatus and also their subjection to the action of the air moving over this surface at a higher rate of speed.

In the illustrated device, the outwardly flared lower end of the tube is provided 45 with an upwardly turned rim or lip 34 which provides a channel extending, as shown in Fig. 5, from a point on the upper face of the helical flange 30 adjacent to the discharge end of this flange around the tube 50 to a point on the underside of this flange slightly back of the discharge end of the flange, the flange being provided with an oblique passage 36 extending from this channel to the edge of said flange adjacent 55 to the inner wall of the casing 2. This passage 36 is preferably so directed through the flange 30, which at this point is thickened somewhat to provide for the passage, that it opens, as shown in Figs. 2 and 4, 60 both at the edge of said flange adjacent to the inner wall of the chamber 2 and in the end face and lower edge of said flange.

This apparatus, like that shown in my prior Letters Patent No. 1,436,100 hereinbefore referred to, has the lower end 4 of

the vaporizing chamber so arranged that it is heated to a much higher degree of heat than the upper part of said chamber whereby any of the less volatile portions of the fuel which may not be vaporized by the action of the heat of the upper part of the chamber and of the air passing thereover will be subjected to this more intense heat of the lower part of the chamber and thus raised to their temperatures of volatilization.

Provision is preferably made for draining off from the lower part 4 of the vaporizing chamber any liquid which may remain unvaporized, even when subjected to the heat of this part of the chamber, and particularly liquid which may accumulate in the chamber when trying to start the engine before the chamber is heated. To this end there is tapped into the lower end of the chamber a nipple 38, itself tapped to receive a cock or ball valve 40, the illustrated device being preferably a ball valve adapted to move to open position when the engine is not running and to be closed by suction of the engine when it is running. With this construction, if an excessive amount of unvolatilized fuel is drawn into the vaporizing device when trying to start the engine and the engine fails to start, the device will automatically drain itself and thus be in condition to operate effectively when the engine starts.

The operation of the device will readily be understood from the foregoing description. As hereinabove suggested, the device is intended primarily for use between the carburetor and the intake of an internal combustion motor, the inlet 28 being connected to the carburetor and the outlet having at its upper end a flange 42 by which it can readily be attached to the intake of the motor.

The fuel mixture coming from the carburetor and entering the inlet 28 will strike the inner wall of the upper cylindrical part 2 of the vaporizing chamber and any of the fuel which has not been vaporized by the action of the carburetor will tend by centrifugal action to strike against this wall as the fuel mixture follows the helical passage down the wall between the outlet tube 24 and the inner face of the wall. This wall, as above pointed out, will be heated by conduction from the lower end of the chamber, the upper part of the wall being, of course, heated to a considerably lower temperature than the lower part whereby the part of the wall which is first encountered by the fuel mixture will be at a temperature which will not tend to crack the more volatile portions of the fuel which may strike it, but will be at a temperature which will facilitate the volatilization of these parts of the fuel.

As the fuel mixture travels down through the helical passage it will of course come to

parts of the inner wall of the chamber 2 which are heated to higher temperatures and the less volatile portions of the fuel, which may not have been volatilized in the 5 upper path of travel, will be subjected to these higher temperatures and their volatilization thus accelerated.

It will be noted that the apparatus is so constructed that the particles of unvolatilized or unvaporized fuel which are thrown against the inner wall of the upper part of the chamber 2 will be spread out upon this wall surface and thus subjected to the action of the air and fuel mixture rapidly traveling through the passage and that even if they are not immediately vaporized and therefore run down to the flange 30, which constitutes the bottom of this helical passage, they will still be exposed to the action 10 of the air and fuel mixture and carried along with it adjacent to the chamber wall to parts of the wall which are heated to higher temperatures. Moreover, if any of the unvolatilized portions of the fuel adhere to 15 the outer surface of the tube 24 they likewise will run down the tube until they strike the helical flange 30, when they will likewise be carried along with the air and fuel mixture to the lower parts of the passage, some of these particles probably, by 20 centrifugal action, traveling across the flange 30 to the chamber wall. Those that still adhere to the tube 24 and run down the tube or follow the flange 30 in a path adjacent to the tube will be caught in the channel formed by the lip 34 and conducted around this channel and through its discharge 36 to the inner face of the chamber wall 2 where they will again be subjected 25 to the action of the heat of this wall surface and to the action of the air and gas mixture traveling over it before entering the outlet into the tube 24.

The cross sectional area of the inlet 28 is 45 preferably the same as the cross sectional area of the passage in the tube 24, and the cross sectional area of the helical passage is also preferably the same as the cross sectional area of the inlet and of the outlet 50 tube.

What I claim as new is:

1. Liquid fuel vaporizing apparatus adapted to be located between the carburetor and intake of an internal combustion motor comprising in combination a chamber having a vertical cylindrical wall, an inlet near the upper end of said wall for the air and fuel mixture, an outlet near the lower end of said wall for said mixture, means for positively confining said air and fuel mixture to a helical path of travel around and along the axis of said chamber as well as down the wall thereof between said inlet and said outlet, and means for heating the 60 lower end of the said chamber.

2. Liquid fuel vaporizing apparatus adapted to be located between the carburetor and intake of an internal combustion motor comprising in combination a chamber having a vertical cylindrical wall, an inlet near the upper end of said wall for the air and fuel mixture, an outlet near the lower end of said wall for said mixture, means for positively confining said air and fuel mixture to a helical path of travel around and along the axis of said chamber and down the wall thereof between said inlet and said outlet, and means for heating directly only the lower end of said chamber.

3. Liquid fuel vaporizing apparatus adapted to be located between the carburetor and the intake of an internal combustion motor and comprising, in combination, a chamber having a vertical cylindrical wall, an inlet near the upper end thereof, a co-axial tubular outlet extending to near the lower end thereof, means positively defining a helical path for the atomized fuel between said chamber wall and said tubular outlet from said inlet to the outlet opening, and means for heating the lower end of said chamber.

4. Liquid fuel vaporizing apparatus comprising a chamber having an upright circular wall, an inlet near the upper end of said chamber directing the fuel tangentially against the said wall, a centrally arranged outlet opening into the chamber near the lower end thereof, means for positively confining the fuel to a helical path around and along the axis of said chamber and down said wall between said inlet and said outlet, said inlet, said helical path and said centrally arranged outlet all having substantially equal cross-sectional areas throughout, and means for heating the lower end of said chamber.

5. Liquid fuel vaporizing apparatus comprising in combination a chamber having a vertical cylindrical wall, an inlet near the upper end thereof directing the fuel tangentially against said wall, a co-axial tubular outlet extending down into said chamber to near the lower end thereof and having an outwardly flared opening into said chamber, means for positively confining the fuel to a helical path down said cylindrical wall between said inlet and said outlet opening, and means for heating the lower end of said chamber, said inlet, said helical path and said tubular outlet all having substantially equal cross-sectional areas throughout.

6. In a device of the class described, a chamber having a vertical cylindrical wall, an outlet for said chamber comprising a tube depending therein to near the lower end thereof, a tangential inlet for said chamber near the upper end thereof, means between said tube and the wall of

said chamber for positively confining the atomized fuel entering said inlet to a helical path about and down the inner wall of said chamber, whereby the unvolatilized portions of said fuel will be mostly thrown against said wall, and means for heating the lower end of said wall to a degree to cause heat to be conducted up said wall for facilitating the vaporization of the unvolatilized portions of the fuel thus striking said wall, said inlet, said helical path and said tube all having substantially equal cross-sectional areas throughout.

7. In a vaporizing apparatus adapted to be located between the carburetor and the intake of an internal combustion motor, means for effecting a centrifugal separation of the unvolatilized from the volatilized portions of the mixture received from the carburetor, comprising a cylindrical chamber having a central tubular outlet depending therein to near the lower end thereof, an inlet near the upper end thereof, and a positively defined helical passage between the wall of said chamber and said outlet tube, of a cross-sectional area substantially corresponding to the respective areas of the inlet and outlet cross sections, and means for so heating the lower end of said chamber that a substantial portion of the heat will be conducted up the vertical walls thereof.

8. Liquid fuel vaporizing apparatus comprising, in combination, a chamber having a vertical cylindrical wall, an inlet near the upper end of said chamber arranged to direct the incoming fuel tangentially against said wall, a coaxial outlet tube extending to near the lower end of said chamber and having an outwardly flared opening into said chamber, means confining the fuel to a helical path down said wall between said tube and said wall from the inlet to the outlet, means for collecting any liquid particles of fuel which adhere to and run down said tube and directing them again to the chamber wall, and means for heating the lower end of said chamber.

9. In apparatus for completing the volatilization of a partly volatilized fuel in a fuel and air mixture, a chamber having a vertical cylindrical wall, means arranged to heat directly only the lower end of said chamber but in such manner as to cause a portion of the heat to be conducted up said wall, an inlet near the upper end of said wall for the fuel and air mixture, an outlet near the lower end, means for positively confining said air and fuel mixture to a helical path of travel around the axis of said chamber and down the wall thereof between said inlet and said outlet, and means for col-

lecting and positively directing to said heated wall all particles of unvolatilized fuel separating from said mixture in its travel between said inlet and said outlet.

10. Liquid fuel vaporizing apparatus comprising, in combination, a chamber having a vertical cylindrical wall, an inlet near the upper end of said chamber, a coaxial outlet tube extending through the top and opening into said chamber near the lower end thereof, means for heating the lower end of said chamber in such manner that a portion of the heat is conducted up said cylindrical wall, means for confining the fuel and air mixture to a helical path down said wall between said tube and said wall from the inlet to the outlet, and means to collect any liquid particles of fuel which run down said coaxial tube and positively to direct them again to the heated chamber wall.

11. In apparatus for completing volatilization of a partly volatilized fuel, a chamber having a vertical cylindrical wall, a coaxial outlet tube extending through the upper end of said chamber and having an outwardly flared opening into said chamber near the lower end thereof, an inlet into the space between said chamber wall and said tube near the upper end of said chamber, an up-turned lip on said outwardly flared lower end of said coaxial tube for collecting any liquid fuel that may adhere to said tube, a conduit for conducting said collected liquid to said cylindrical wall, and means for heating the lower end of said chamber in such manner that a portion of said heat is conducted up said cylindrical wall.

12. Apparatus for completing volatilization of a partly volatilized liquid fuel comprising, in combination, a chamber having a cylindrical wall provided with an inlet near its upper end, means for heating the lower end of said chamber in such manner that heat is conducted up said wall, a coaxial outlet tube extending through the upper end of said chamber and having an outwardly flared opening into said chamber near the lower end thereof, means extending between said cylinder wall and said tube for confining the fuel to be volatilized to a substantially helical path down said wall from said inlet to said outlet, and a channel about the lower end of said tube arranged to collect both the unvolatilized liquid that runs down said tube and that which runs down said means adjacent to said tube and to direct said liquid to said cylinder wall.

Signed at New York city this 9th day of February 1923.

WILLIAM H. HILL.
